(57) **CLAIM**

I claim the ornamental design for a golf ball, as shown and described.

DESCRIPTION

The nature and intended use of the article in which the design is embodied is golf ball for use in playing the game of golf.

FIG. 1 is a front elevational view of a golf ball showing my new design;

FIG. 2 is a rear elevational view thereof;

FIG. 3 is a left elevational view thereof;

FIG. 4 is a right elevational view thereof;

FIG. 5 is a top plan view thereof; and,

FIG. 6 is a bottom plan view thereof.
